UNITED STATES PATENT OFFICE

154,086

DESIGN FOR A PIPE HOLDER

Walter E. Weaver, Nacogdoches, and Vascar N. Bridges, Houston, Tex.; said Bridges assignor to said Weaver

Application October 30, 1947, Serial No. 142,229

Term of patent 14 years

(Cl. D85—8)

To all whom it may concern:

Be it known that we, Walter E. Weaver and Vascar N. Bridges, citizens of the United States of America, residing at Nacogdoches, county of Nacogdoches, and Houston, in the county of Harris and State of Texas, respectively, have invented a new, original, and ornamental Design for a Pipe Holder, of which the following is a specification, reference being had to the accompanying drawing, forming a part thereof wherein:

Fig. 1 is a front elevational view of a pipe holder, showing our new design;

Fig. 2 is a side elevational view thereof; and

Fig. 3 is a top plan view thereof.

The dominant features of our design reside in the portions shown in full lines.

We claim:

The ornamental design for a pipe holder, as shown and described.

WALTER E. WEAVER.
VASCAR N. BRIDGES.
